UNITED STATES PATENT OFFICE.

EDWIN TAYLOR AND EDWARD F. CHANDLER, OF BROOKLYN, NEW YORK, ASSIGNEES
TO TAYLOR LABORATORIES INC., A CORPORATION OF NEW YORK.

ELECTROLYTIC APPARATUS.

Original application filed December 2, 1919, Serial No. 341,953. Divided and this application filed March 19, 1926. Serial No. 95,914.

This invention relates to improvements in electrolytic apparatus and this application is a division of our prior application Ser. No. 341,953 filed December 2, 1919. In our prior co-pending application for United States Letters Patent, Ser. No. 314,102, filed July 29, 1919, we have described a process wherein organic material such as cellulose in a fibrous or cellular condition may be converted by dissolving the cellulose in a suitable solvent, such as cupro-ammonia solution and electrolyzing the solution between a suitable anode and cathode whereby cellulose substantially free of the solvent chemicals is deposited on the anode and the copper is deposited on the cathode and ammonia is freed. The main object of the present invention is to provide improvements whereby such organic matter may be so treated more expeditiously and in a more economical and useful manner. Further and more specific objects, features and advantages will more clearly appear from the detail description given below. In the preferred method of practicing the inventive idea the organic or cellulose material to be converted is dissolved preferably in an excess of cupro-ammonia solution, filtered to remove extraneous impurities, the solution concentrated by the partial removal of ammonia and water (as for instance by means of a vacuum), the resulting homogeneous fluid flowed on a carrier which may be a flexible band of metal suitable for employment as one of the elements of an electrolytic cell, the said carrier being adapted to convey the flowed material through preferably a dry and inert gas, thereby excluding deleterious atmospheric contamination. The carrier conveying the flowed material now enters and becomes preferably one of the elements or electrodes in a bath which may be provided with another element or electrode so as to constitute an electrolytic cell upon the energization of the said elements and through which the carrier which may be the anode, is adapted to continuously convey the flowed material. Owing to the electrolytic characteristics of cellulose in a colloidal state, the flowed material as it passes through the influence of the said electric field or fields is converted from the colloidal solution to a solid or more dense state which transformation should be completed under proper conditions of time and current density before the carrier and material leaves the cell. During the period of transformation the volatile constituent is released from the mass and is in a condition to be conveyed to a suitable condensing or recovering system, the metallic constituent being deposited on the cathode in recoverable condition. The transformed organic material free of all traces of any ingredient that might cause future deterioration is preferably conveyed through a suitable washing system where any adhering or extraneous traces of foreign materials are removed and thence to a suitable drying system for the removal of any moisture content after which the converted material is ready for separation from the conveyor or carrier. This separation may be effected by means of a V-shaped fixed edge supplemented by two rolls.

The material, now in a transparent flexible band resembling celluloid in appearance is then led through a bath containing a volatile solvent such as amyl-acetate which possesses a slight solvent or softening effect on the cellulose and materially aids in increasing its surface lustre, its density, and its resistance to moisture. The material still wet with solvent is now passed through warm calender rolls whereon it is surfaced, brought to exact thickness and dried and the solvent recovered. From the calenders the finished product may be wound on reels, cut or trimmed in sheets or strips or otherwise disposed of.

It will be seen that this process is economical, as well as continuous. All the solvent materials are recovered in usable form for re-solution, even the trimmings from the finished material being returned to the solution tanks. The power factor is low and the amount of labor required is almost negligible. It is evident that the above process can be advantageously carried out by the use of a concentrated zinc chloride solution, etc., in place of the cupro-ammonia.

In the accompanying drawings we have illustrated a suitable application of our invention as applied to the manufacturing of

photographic films. In said drawings, Fig. 1 illustrates in vertical cross-section, parts being broken away, the arrangement of a suitable plant for manufacturing photographic films, and Fig. 2 is an enlarged cross-sectional detail of the endless belt and film formed thereon.

3-4 indicates suitable tanks carrying concentrated solution of cupro-ammonia or 10 concentrated solution of zinc chloride both being good solvents for cotton which may be used in the manufacturing of the film. About one pound of cotton may be used to about twenty pounds of the solution and suitable 15 means such as the valve 5 may be provided for regulating the flow of the material upon the endless belt 6 which passes entirely through the closed tray or chamber 7 as shown.

20 The belt may be made of copper and may be plated with other metal and buffed and may be suitably perforated as indicated at 8 in Fig. 2 to receive the teeth of sprocket wheels for driving the same, suitable means 25 for driving the belt being provided such as 9, an electric motor connected to the driving shaft 10. Upon the belt may be provided suitable strips of material such as 11 between which the flowing material from the tanks 30 3-4 is deposited. In the drawing I have illustrated the belt as traveling from left to right looking at Fig. 1.

The ammonia from the closed tray 7 is 35 drawn through the outlet pipe 12 by the suction fan 13 and is passed through the drying chamber 14 provided with suitable grids 15 upon which lime or other suitable material 15' may be piled, the dry ammonia returning through the pipe 16 into the closed 40 tray 7 as shown. This provides a constant circulation of dry ammonia gas in the closed chamber 7 and prevents waste of material and contamination from the outside.

45 17 indicates an electrolytic cell to be hereafter more fully referred to and is in communication with the superimposed chamber 18 through which ammonia, hydrogen, oxygen or other gases rise and escape by way of the pipe 19 controlled by the valve 20 into the chamber 21 escaping under the hood 22 for condensation and recovery except when the valve 23 is open to allow the same to pass to the drying chamber 14.

The electrolytic bath 17 may be provided 55 with copper electrodes 24 or when the process is worked with zinc chloride, zinc electrodes may be used. An acidulated solution of nitric or sulphuric acid 25 is provided as an electrolyte sufficiently strong to carry the 60 current.

As the cellulose fed upon the belt 6 passes 65 down through the chamber 18, it passes beneath the first electrode 24 at the right side of the figure over the pulley 26, beneath the next electrode, over the next pulley and so

on until it enters the chamber 27, said pulleys being driven by the worms 28 upon the motor shaft 10 and said electrodes being connected to the negative side of a suitable source of electricity as shown, with the result that 70 the metallic content of the cellulose upon the belt is electro-deposited therefrom upon the electrodes 24 leaving the cellulose gradually becoming white instead of blue or green as it passes through the electrolytic bath until 75 upon leaving said bath the cellulose is quite white, whereupon it enters the washing tank 27 before referred to. The film is now sufficiently tough and flexible for washing whereas if the metallic content remained in 80 the film, it would upon drying be brittle and liable to break up. In the washing tank 27 water enters by the pipe 29 controlled by the valve 30 and escapes by the pipe 31 which may be provided with a valve 32, the film 85 passing over the pulleys 33 driven by the worms 34 upon the said motor shaft 10, and a suitable partition 35 may be provided with an opening at the bottom as indicated at 36 so as to bring the film in contact with the 90 cleaner water of the wash as it leaves the tank 27. All of these tanks are preferably closed to prevent foreign matter from coming in contact with the film and if desired suitable means may be provided for evacuating air therefrom as any carbonic acid present in the room is apt to form carbonate, and various other objectionable results may be 95 encountered. This especially applies to the drying tank. The washing tank removes 100 any adhering ammonia, acid, or particles of matter, after which the film passes to the drying chamber 37 where it again passes over pulleys such as 38 driven by worms such as 39 and beneath pulleys such as 40 until it 105 finally emerges over the pulley 41 as shown. This drying tank may of course be heated by any suitable means to a temperature, say perhaps 120 degrees Fahrenheit. The film is now loosened from the belt upon which it 110 was formed and due to the heat, shrinkage, etc., is readily separated therefrom, and in this connection a suitable knife or stripper such as 42 may be provided adjacent the periphery of the roll 41 so as to allow the film to pass leftwardly between the rollers 43 of the tank 44 while the belt or carrier passes downwardly beneath the pulleys 45 from which point it returns to the starting 115 place and again passes through the closed tray 7.

The detached film upon entering the tank 44 passes over the roller 46 driven by the worm 47 and downwardly through the amyl-acetate bath 48 passing upwardly again over the roller 49 and upon the rolls 50 preferably of highly polished surface. In the amyl-acetate tank the film is softened, densified, and is increased in its resistance to moisture, after which, upon passing first leftwardly 120

around the top roll 50, then rightwardly around the next roll below, and leftwardly again, and so on alternately, it becomes thoroughly dried and finished and is wound upon the reel 51, while the amyl-acetate vapors escaping through the outlet 52 may be condensed for re-use, thus providing a continuous, economic, and practical method of producing film in which there are practically no losses, but complete recovery of materials, the film being adapted to travel through the system with a speed of production higher than in any of the present well known methods, while at the same time producing a film of greater transparency and durability, one which is practically non-combustible and of numerous other properties and advantages.

One of the advantages in the use of our film for photographic purposes is that it may be impregnated from one side (preferably uncalendered) with a solution of silver salt, such as nitrate of silver, after which the film may be exposed to an atmosphere of, and impregnated with bromine, chlorine, iodine or a combination thereof, thereby depositing insoluble bromide or chloride etc. of silver in the film itself. It will be found that by preparing photographic films in this manner that after the same has been photographically exposed and developed there is no flaking off or scratching off of the negative surface, thus preventing the objectionable effects in photography so much complained of, as even if the surface of our film be scratched or mutilated, the chemicals having penetrated the film, still present the photographic image, which in the path of the light registers the characters, notwithstanding the mutilated surface of the film.

Another advantage of our process resides in the fact that by passing the film from the drying chamber 37 through any well known form of nitrate bath of any desired consistency, a pyroxyline may be obtained in a dense continuous sheet having the same nitrogen content as the original cotton immersed under equal conditions in the same bath. This provides a ready means for manufacturing granulated smokeless powder without the use of a volatile solvent.

The cupro-ammonia solution hereinbefore referred to is preferably made by dissolving hydrated cupric-oxide CuH_2O , in approximately an equal weight of ammonia water containing thirty per cent (30%) ammonia hydrate NH_4OH . The resulting solution is of an intensely blue color and may be considered to be merely a mixture of cupric-oxide, (CuO) ammonia (NH_3) and water. We have found even under adverse conditions that with about two amperes per square inch of anode, that we can obtain about forty grams of cellulose and about twenty-three and one-half grams of cop-

per in about an hour and a half. This however is not submitted as an accurate statement as to what may be done under more favorable conditions.

While we have described our improvements in great detail and with respect to a preferred form thereof, we do not desire to be limited to such details or form since many changes and modifications may be made and the invention embodied in widely different forms without departing from the spirit and scope thereof in its broader aspects.

What we claim as new and desire to secure by Letters Patent is:—

1. In an apparatus of the class described, the combination of an electrolytic cell substantially closed to the outside atmosphere, a chamber substantially closed to the outside atmosphere, means for passing a carrier through said chamber and cell and means for applying to said carrier in said chamber, material to be electrolyzed in said cell.

2. In an apparatus of the class described the combination of a chamber substantially closed to the outside atmosphere, an electrolytic cell, means for passing a carrier through said chamber, means for applying to said carrier in said chamber material to be electrolyzed in said cell, and means whereby said material is passed continuously from said chamber through said cell to be electrolyzed therein.

3. In an apparatus of the class described the combination of a chamber substantially closed to the outside atmosphere, an electrolytic cell substantially closed to the outside atmosphere, means for passing a carrier through said chamber, means for applying to said carrier in said chamber material to be electrolyzed in said cell, and means whereby said material is passed through said cell to be electrolyzed therein, and means for withdrawing gases from said chamber and cell.

4. In an apparatus of the class described, the combination of an electrolytic cell substantially closed to the outside atmosphere, and a moving carrier passing into and out of the electrolyte in said cell, whereby material may be electrolyzed on the carrier in the cell, and means for stripping the material electro-deposited on the carrier in the cell, from the carrier after it leaves the electrolyte in the cell.

5. In an apparatus of the class described, a continuous metallic belt and an electrolytic bath, said belt being electrically connected to the positive terminal of a source of electric current and a metallic cathode in said bath and means for moving the belt continuously while said electrical current is applied.

6. In an apparatus of the class described, the combination of an electrolytic bath, a car-

rier moving through said bath, said carrier moving the carrier through the bath where-
being connected to one terminal of a source by the material is electrolyzed in the bath.
of electric current to form one electrode in
the bath, an opposite electrode in the bath,
means for applying to the carrier before it
enters the bath, material to be electrolyzed
on the carrier in the bath, and means for
In testimony whereof we have signed our 10
names to this specification.
